Atty.

UNITED STATES PATENT OFFICE.

FREDRIK LJUNGSTROM, OF BREVIK, LIDINGON, SWEDEN, ASSIGNOR TO AKTIE-BOLAGET LJUNGSTROMS ANGTURBIN, OF STOCKHOLM, SWEDEN, A CORPORATION.

TURBINE-DRIVEN LOCOMOTIVE.

1,422,111.

Specification of Letters Patent.

Patented July 11, 1922.

Application filed October 19, 1921. Serial No. 508,896.

To all whom it may concern:

Be it known that I, FREDRIK LJUNGSTROM, Chief Engineer, subject of the King of Sweden, residing at Brevik, Lidingon, 5 Sweden, have invented certain new and useful Improvements in Turbine-Driven Locomotives, of which the following is a specification.

In locomotives in which the driving wheels 10 are driven by means of turbines by the aid of crank and connecting rod, for instance with assistance of toothed gearings, and provided with a boiler carriage and a condenser placed on a separate carriage it has 15 been proposed to place aggregates of toothed gearings connected with the turbine on the condenser carriage. In the case of large locomotives it has proved difficult to place within the limited space a system of toothed 20 gearings together with a turbine producing the whole amount of power of the locomotive.

This invention relates to an arrangement in locomotives of the first-named type and 25 its object is to dispose the turbine systems and the corresponding driving devices in such manner that locomotives of considerably greater efficiency than has hitherto been the case may be manufactured. The invention 30 consists chiefly in that one or more high pressure turbine systems and corresponding driving devices, for instance toothed gearings, are mounted on the boiler carriage and one or more low pressure turbine systems 35 and corresponding driving devices, for instance toothed gearings, on the condenser carriage. By this the advantage is obtained that the necessary flexible steam conduit connection between the two carriages may 40 be placed in a steam pipe of smaller diameter than is the case, if two turbine systems independent of each other be mounted on either carriage, since in this case the said connection has to be placed in an outlet 45 conduit from a turbine to the condenser, this conduit being necessarily of considerably greater diameter.

In the accompanying drawing Figures 1 and 2 illustrate different embodiments of the 50 invention.

Referring to the drawing, the boiler carriage is indicated by 1 and the condenser carriage by 2. In the embodiment shown in Fig. 1 there is mounted a toothed gear 55 system together with the turbine on either

carriage, the whole high pressure system being collocated at a place in the boiler carriage and the whole low pressure system at a place in the condenser carriage. The high pressure turbine system is indicated 60 by 3 and the low pressure turbine system by 4. The waste steam from the turbine system 3 is conducted to the turbine system 4 from one carriage to the other, and in the steam conduit between the systems a joint 65 or flexible connection 5 is arranged. The waste steam from the turbine system 4 is conducted directly to the water tank of the condenser. Each turbine is connected with a toothed gearing transmitting power to the 70 driving wheels by means of crank and connecting rod. Said turbine systems with toothed gearings may also be mounted at any other place on the carriages, as for instance on the foremost part of the boiler 75 carriage and the rearmost part of the condenser carriage. It is however more advantageous to place the systems in such manner that the shortest possible steam conduits are obtained.

According to the embodiment shown in Fig. 2, two turbine systems together with toothed gearings are disposed on either carriage and placed at each end of the carriage. Also in this case the systems placed 80 on the boiler carriage consist of high pressure turbines and the systems on the condenser carriage of low pressure turbines. As will appear from Fig. 2, the waste steam is conducted from the system 6 on the foremost part of the boiler carriage to the system 7 on the rearmost part of the same carriage and then to the system 8 on the foremost part of the condenser carriage. The steam is then conducted to the system 9 on 85 the rearmost part of the condenser carriage and finally to the water tank of the condenser carriage 2. The steam conduit between the two carriages is also in this case provided with a flexible connection 5. The 90 turbines may also be disposed in other manner provided the waste steam from the turbines of the boiler carriage be not conducted directly to the condenser, since in this case an outlet conduit with a diameter 95 too great to make a suitable arrangement of a flexible connection possible will be necessary. The toothed gear systems with turbines may be disposed on bogies or on rigid frames. The system 6 is altogether placed 100 105 110

on a bogie, and owing thereto the steam conduits to the same are to be made flexible, for instance by the aid of long pipes. The system 9 is altogether placed on the condenser receptacle or the carriage frame, and therefore the driving device is arranged in a manner known from the construction in which the machine is disposed on the frame and the driving device on a bogie. The driving device on the rearmost part of the boiler carriage is preferably disposed below the coal bunker 10 placed on the boiler carriage.

What I claim as new and desire to secure by Letters Patent of the United States is:—

- 15 1. In locomotives in which the driving wheels are actuated by turbines with the assistance of toothed gearings, and provided with a boiler carriage and a condenser placed on a separate carriage, the arrangement that one or more high pressure turbine systems with driving devices are disposed on the boiler carriage and one or more low pressure turbine systems with driving devices are disposed on the condenser carriage.
- 20 2. An arrangement according to claim 1, characterized by a high pressure turbine system with a driving device consisting of toothed gearing, being disposed on the rear part of the boiler carriage and a low pressure turbine system with a driving device consisting of toothed gearing, on the fore part of the condenser carriage.
- 25 3. An arrangement according to claim 1, characterized by a turbine system with driv-

ing device, consisting of toothed gearing, being disposed at either end of both carriages.

4. An arrangement according to claim 1, 40 characterized by a turbine system with driving device, consisting of toothed gearing, being disposed at either end of both carriages on bogies.

5. In locomotives in which the driving 45 wheels are actuated by means of crank and connecting rods with the assistance of toothed gearings, and provided with a boiler carriage and a condenser placed on a separate carriage, the arrangement that one or 50 more high pressure turbine systems with driving devices are disposed on the boiler carriage and one or more low pressure turbine systems with driving devices are disposed on the condenser carriage. 55

6. In locomotives in which the driving wheels are actuated by means of crank and connecting rods with the assistance of toothed gearings, the arrangement of a high pressure turbine system with a driving device consisting of toothed gearings, being disposed on the rear part of the boiler carriage and a low pressure turbine system with a driving device consisting of toothed gearings, on the fore part of the condenser 60 carriage.

In testimony whereof I affix my signature in presence of two witnesses.

FREDRIK LJUNGSTROM.
